UNITED STATES PATENT OFFICE.

JOSEPH A. GROEBLI, OF NEW YORK, N. Y.

BEAD-SEWING MACHINE.

Application filed January 12, 1924. Serial No. 685,772.

To all whom it may concern:

Be it known that I, JOSEPH A. GROEBLI, a citizen of the United States, and a resident of the city, county, and State of New York, have invented certain new and useful Improvements in Bead-Sewing Machines, of which the following is a specification.

My invention relates to that class of bead sewing machines wherein beads loosely strung upon a thread are fed along the thread, while the thread itself is carried forward; and my improvements are particularly directed to means for automatically controlling the slack and travel of the bead thread, in connection with and through the beads, so that the progress of the thread shall be substantially uniform, and the disadvantages arising from having too much or too little free thread, as it is drawn off the reel, shall be avoided.

These improvements are advances in the art over what has been shown, for instance, in my Letters Patent No. 1,445,764, of February 20th, 1923; and the application of my present inventions will be readily understood by referring to my aforesaid patent for an illustration of those parts of the old mechanism which are not shown in the drawings of this application.

In the drawings, Fig. 1 is an elevation illustrating the novel features of my improved mechanism; Fig. 2 is a similar view taken from the reverse side of the machine, some of the driving mechanism being also shown; Fig. 3 is an elevation looking to the right on Fig. 1, the lower portion of the mechanism being omitted; and Fig. 4 is a detail in plan of part of the operating mechanism.

In all the figures similar parts are designated by corresponding reference numerals.

The shafts 10 and 13 correspond respectively to the shafts 10 and 13 of my aforesaid patent, and indicate means by which the operative power is transmitted to the feeding and stitch forming mechanisms. The functions to be performed by the tube 53 corresponds with those of the tube similarly numbered in my aforesaid patent.

From the driving shaft 10, through the gears 11 and 12, shaft 14 and gears 15 and

16, connection is made with the shaft 17, through which the mechanism for tensioning and unwinding the bead thread and feeding the beads is actuated.

The shaft 17 carries a cam 25 against which travels a roller 26 on an arm 27 pivoted at 28 to the frame work of the machine, the roller being held to duty on the cam by suitable means such as a spring 29 between the arm 27 and the machine frame. To one end of the arm 27 is pivoted one end of a rod 30, which, at its other end, is pivoted to one arm of the bell crank 31 and journaled in the frame of the machine, the other arm 32 of the bell crank carrying a transverse element 33 and corresponding in function with bead feeder 64 of my aforesaid patent, the cooperating bead feeder 34 being also pivoted to the head of the machine, so that it may be raised by the arm 32, and allowed to drop again, to allow the beads to pass the feeders one by one.

To the arm 31 is also pivoted a driving pawl 37, which engages with the ratchet wheel 38 on shaft 39, journaled in the frame work of the machine, and which carries a feed wheel 40, over which the thread and beads travel to the tube 53 through which they pass down to the stitching mechanism.

When, therefore, the shaft 17 and cam 25 revolve, the bead feeders 33 and 34 will be reciprocated once, and the feed wheel 40 will be turned one step for each revolution of the shaft 17.

The shaft 17 also carries another cam 45, against which travels a roller 46 on arm 47 of pivoted bar 48, the roller being kept to duty by a suitable spring 49 between the bar and the machine frame.

The bar 48 through rod 50 rocks an arm 51 journaled upon the end of the shaft 52, which also carries the thread and bead reel 57.

The arm 51 also carries a pawl 54 engaging with ratchet wheel 55, carried by the shaft 52, the pawl 54 being held to duty by a suitable spring 56. A spring 58, cooperating with a flange 59, acts as a frictional brake on the wheel 55.

The rotation of the cam 45 will, there-

fore, rock the arm 51 up and down, with a uniform stroke for each revolution of the shaft 17.

In a bracket 60, supported by the frame 5 work of the machine, is journalled a shaft 61 carrying an arm 62, provided at its free end with a cam 63 against which rests a pin 64 carried near the free end of the pawl 54; so that if the cam is rocked down it will, 10 through the pin 64, push the pawl out away from the ratchet wheel 55, and will prevent the pawl from engaging with the ratchet wheel until it has slid some distance down the cam, the distance depending upon the 15 extent to which the cam is depressed. The shaft 61 also carries an arm 66 on the end of which is journalled a roller 67 behind which passes the bead thread 68. The arm 66 and the cam 63 are normally rocked in- 20 ward toward the ratchet wheel 55 by a spring 69 stretched between an arm 70 on the shaft 61, and the frame work of the machine.

It will be seen, therefore, that while the 25 stroke of the ratchet arm 51 will be uniform in extent for each revolution of the shaft 17, the extent to which it will turn the ratchet wheel 55 will be governed by the inclination of the cam 63. If the free part 30 of the bead thread 68 is quite long, the roller 67 and arm 66 will be swung out by the thread, away from the reel 57, and the shaft 61 will be correspondingly rocked, raising the cam 63, so that the claw of the pawl 64 35 will engage with the ratchet wheel 55 higher up than is, for instance, shown in the figures, which indicate the position of the elements with a fairly long free thread. Thus, if in 40 the position of the parts shown in the drawings the ratchet would engage with the wheel 55, so as to turn it one cog space, by the raising of the cam 63, so as to let the pawl fall closer to the ratchet wheel 55, it will engage with the ratchet wheel further 45 up and turn it an increased distance according to the extent to which the cam 63 is raised.

Thus the stitching drag on the bead thread 50 is utilized to automatically accelerate or retard the turning of the reel 57 and the releasing of the thread and beads therefrom, while the driving mechanism maintains a uniform movement of the bead and thread 55 forwarding mechanism, the accumulation of too much or two little free thread is guarded against by providing for positively speeding up the movement of the thread reel, so as to release more thread, as may be required by the stitching mechanism.

I desire it to be understood that the mechanism that I have illustrated is to be considered as a typical and not as an exclusive form of the embodiment of my invention. For it will be understood by those skilled in 65 the art that details of construction and ar-

rangement may be modified, as by the use of mechanical equivalents, without departing from the spirit of my invention as claimed.

Having thus described my invention, what I claim and desire to secure by Letters Patent of the United States, is:—

1. The combination, in a bead sewing machine, embodying mechanism for forming stitches employing a bead thread carrying loosely strung beads, of a primary bead 75 thread supply reel, means, other than the thread, for positively driving the reel, and automatic means for governing the operative action of the driving means.

2. The combination, in a bead sewing machine, embodying mechanism for forming 80 stitches employing a bead thread carrying loosely strung beads, of a primary bead thread supply reel, means, other than the thread, for positively driving the reel, and 85 automatic means, controlled by the drag of the thread, for governing the operative action of the driving means.

3. The combination, in a bead sewing machine, embodying mechanism for forming 90 stitches employing a bead thread carrying loosely strung beads, of a primary bead thread supply reel, intermittently acting means, other than the thread, for positively driving the reel, and automatic means, controlled by the drag of the thread, for governing the operative action of the driving 95 means.

4. The combination, in a bead sewing machine, embodying mechanism for forming 100 stitches employing a bead thread carrying loosely strung beads, of a primary bead thread supply reel, means, other than the thread, for positively driving the reel, and automatic means, controlled by the drag of the thread, for governing the extent to which 105 the reel is turned by the driving means.

5. The combination, in a bead sewing machine, embodying mechanism for forming 110 stitches employing a bead thread carrying loosely strung beads, of a bead thread reel, reel driving means including a ratchet and reciprocating pawl, and automatic means, controlled by the drag of the thread and including means for limiting the operative engagement of the pawl with the ratchet, for governing the operative action of the driving 115 means.

6. The combination, in a bead sewing machine, embodying mechanism for forming 120 stitches employing a bead thread carrying loosely strung beads, of a bead thread reel, reel driving means including a ratchet and reciprocating pawl, and automatic means, controlled by the drag of the thread and including a cam for limiting the operative engagement of the pawl with the ratchet, for governing the operative action of the driving 125 means.

7. The combination, in a bead sewing ma- 130

chine, embodying mechanism for forming stitches employing a bead thread carrying loosely strung beads, of a bead thread reel provided with a ratchet wheel, driving means including a reciprocating pawl engaging with the ratchet wheel, and automatic means including a swinging arm en-

gaging the thread and movable into varying positions by the drag of the thread, and a cam moveable by the arm to limit the engagement of the pawl with the ratchet wheel. 10

JOSEPH A. GROEBLI.
